PC(57) **CLAIM**

The ornamental design for a motor for railway vehicle, as shown and described.

DESCRIPTION

FIG. 1 is a front perspective view of the front, bottom, and left sides of a motor for railway vehicle showing my new design;

FIG. 2 is a rear perspective view of the rear, top, and right sides thereof;

FIG. 3 is a front view thereof;

FIG. 4 is a rear view thereof;

FIG. 5 is a top plan view thereof;

FIG. 6 is a bottom view thereof;

FIG. 7 is a right side view thereof;

FIG. 8 is a left side view thereof; and,

FIG. 9 is an enlarged view of taken along lines 9-9 of FIG. 1.

The broken lines shown represent portions of the motor for railway vehicle and form no part of the claimed design.
